UNITED STATES PATENT OFFICE.

BENJAMIN F. STEPHENS, OF BROOKLYN, NEW YORK.

APPARATUS FOR DIGGING WELLS.

SPECIFICATION forming part of Letters Patent No. 274,988, dated April 3, 1883.

Application filed October 9, 1882. (No model.)

To all whom it may concern:

Be it known that I, BENJAMIN F. STEPHENS, of Brooklyn, in the county of Kings and State of New York, have invented an Improvement 5 in Apparatus for Digging Wells, of which the following is a specification.

These improvements are especially adapted to digging wells of a large size, and to any desired depth, regardless of water that may 10 accumulate in the well, and the special features of novelty are hereinafter set forth.

In the drawings, Figure 1 is a vertical section of a well and the apparatus in use. Fig. 2 is a detached view in larger size of the cage, 15 partially in section. Fig. 3 is a plan view of the cage. Fig. 4 is a sectional plan of the collar for the hoist-rope. Fig. 5 shows the wrench-bar for revolving the central shaft. Fig. 6 is one of the joints of the shaft. Fig. 7 is a plan 20 of the circular bearing for the central shaft. Fig. 8 is a section of the same at x x , Fig. 7, and Fig. 9 represents a portion of the lower part of the steining.

I make use of curbs or Steinings that are 25 filled with bricks or stone to form the lining of the well. These Steinings sink as the well is excavated. I use a central shaft, that forms a guide for a cage to be raised and lowered, and also a means for revolving the cage. 30 Upon this cage are buckets, that are used to excavate the sand, and the same are drawn up with the cage. By this means it is not necessary to descend into the well, and the excavation is made uniformly at any desired depth, 35 and below the water.

It is to be understood that this improvement is only available with sand, gravel, or comparatively soft material, and that if large stones or rocks are struck in excavating the 40 well they must be removed in any of the well-known modes, as my invention is available only in cases where the soil is sandy, or where the water renders soft the materials, so that it may be excavated by the buckets.

The curb or steining of the well is made in 45 the usual manner, except that the bottom or lowest section of the steining is to be larger at the bottom than at the top, to facilitate the sinking of the steining as the excavation beneath it progresses. The lower section, A, is composed of the bottom ring, a , of timber, and

two or three rings above it, (marked b ,) and the exterior planking, c . The inside is filled in tightly with brick or stone, laid up by preference in cement. There may be two or more 55 sections, B, above the steining A, each made in the same manner, except that the upper sections have parallel sides.

In putting down this well the surface earth is excavated to a convenient depth, sufficient 60 for receiving the lower part of the steining A. It is often advantageous in wells of large diameter that are to be sunk to a considerable depth to excavate the surface earth to the water-level, or nearly so, and then to place or 65 construct the steining A in the proper position. Where the well is small the excavating appliances hereinafter set forth are available before the water is reached. I provide a platform, d , resting upon the upper steining and 70 provided with two flaps, d' , hinged to the frame of the platform, so that these can be opened to allow the excavating-cage to be drawn out or introduced into the well and closed for the workmen to stand upon during the other operations. There is a frame, E, rising above 75 the platform the proper height to form a central guide for the excavating-axis of the well. This axis e is made of square or polygonal bars, beveled at the ends, lapped and bolted together, 80 as at 3, Fig. 6. At the lower end of this axis is a disk, e' , for supporting the weight of the shaft and preventing its sinking too rapidly into the earth. If the earth is soft the disk e' will be larger than it is for hard gravel, and if 85 the earth or gravel is very hard the disk may be dispensed with. This axis is guided at the upper end by being passed through a hole in the cross-frame E; or there may be a revolving circular guide-plate, e^2 , with a hole in it for the 90 passage of the central axis, e . The cage that is employed for excavating is to be drawn up and lowered down upon this axis e , and by the same it is to be rotated, as hereinafter described.

The cage is composed of the arms f , that are united at the center and provided with an opening, through which the axis e passes, and with rollers h at each side of this axis, so that the parts are guided and move with but little 100 friction. The outer ends of the arms f are united by the ring or braces h^2 , and there is a

head-piece, *k*, that is connected to the arms *f* by the tie and brace rods *l m*. This head *k* has an opening through it for the passage of the axis *e*, and it also has anti-friction rollers 5 *h'* at the sides of the square axis. I remark that the parts through which the axis *e* passes are made of a size and shape to fit that axis, but to slide freely thereon, and there are notches that allow the cage to be moved up or 10 down over the heads of the bolts which unite the sections of the axis *e* together. At the outer ends of the arms *f* there are rollers *g*, that roll easily against the interior surface of the well should the parts come into contact in 15 raising or lowering the cage.

In order to raise and lower the cage I make use of a chain or rope, *p*, that passes from any suitable hoisting apparatus over a pulley on the frame *E* down to a collar, *o*, that surrounds 20 the head-piece *k*, and is within a neck that is formed around such head-piece. This collar can be moved freely around the neck, so that the rope can be caused to draw up straight, by giving it a shake at the upper end 25 and causing the collar to slip around in the neck. This is of importance, because the rotating of the cage, as hereinafter explained, tends to wind the hoisting rope or chain around the axis *e*, and this collar allows the 30 lower end of the rope to be moved around to unwind it from around the axis.

There are mortises through the arms *f* at suitable distances apart, and into these are inserted movable bolts adapted to the reception 35 of buckets, forks, stirring-plows, &c., used in excavating at the bottom of the well. The knife or colter *t* is attached by the screw in one of these mortise-holes, the plow *u* in another mortise-hole, and the fork or scraping-fingers *v* in another mortise, and the buckets or pails *w*, with handles *x* and attaching-screws *y*, are applied at other of the mortise-holes. These parts are to be placed in the 40 proper relative positions on the respective arms, so as to do the excavating in the most reliable manner. Usually there will be four buckets—two placed at the outer mortises of opposite arms and the other two buckets at the inner mortises of the intermediate arms—45 the colters or knives, plows, and forks being interspersed with reference to loosening the earth, sand, or other material at the bottom of the well, and then scraping it up by the buckets.

50 It is important that the buckets, as they fill with water, shall all turn in one direction, so that they may lie on the earth or sand with their mouths in the direction in which they are moved by the rotation of the cage. I accomplish this by fastening upon one side of each bucket a weight, which will tend to sink down this side first into the water, and hence the weighted side will always be downwardly and fill with water.

55 After the cage has been lowered down, the axis *e* is to be rotated by the workmen applying forked handspikes 20 to the shaft *e* and

walking around upon the platform *d d'*. This causes the earth to be loosened and scraped up into the buckets. The hoist rope or chain 70 is then shaken to cause it to hang vertically, and the cage and buckets are drawn up, the flaps *d'* opened to allow the same to pass, the flaps closed, the buckets emptied, the flaps opened, and the buckets again lowered into 75 the well, and the operations repeated. The weight of the axis will cause it to descend and penetrate the earthy material as the excavation progresses, and the weight of the steining will cause the earthy materials to 80 be displaced toward the middle of the well and within reach of the buckets. This will be easily done in cases where the sand or earth is soft and wet, and under all circumstances the excavation can be made at a sufficient depth below the steining, and of a uniform depth, so that the earth will break away 85 and fall into the excavation, and the steining will descend vertically and uniformly. If there is any tendency to settle at one side of 90 the steining more rapidly than the other, it may be prevented by a frame-work upon the surface of the earth provided with guide-rollers.

In excavating the well strata of clay are 95 sometimes met with, and the bottom edge of the steining resting upon such clay excludes the water, and the excavation cannot be carried on to advantage, except when the water flows into the well and loosens up the material 100 to be removed. To prevent this difficulty I slot the lower edge of the steining vertically, as seen at *b'*, Fig. 1, and in the partial elevation, Fig. 9. These slots allow the water to 105 flow into the well after the steining rests upon a strata of clay or similar material, and if the well is dug deep the flowing water cuts channels in the clay as the steining descends, and besides this, the steining being slightly conical, there is a space left around the steining 110 as it descends. The axis is guided at the upper part of the frame by the circular bearing-piece *l'*, that has an opening through it of a shape to allow the axis to pass freely through it, and this bearing-piece is in a recess in the 115 cross-piece of the frame, so that it can turn around freely with the axis; but the axis will slide vertically through this bearing-piece as the excavation progresses.

I am aware that a vertical shaft has been 120 revolved by capstan-bars, and that upon this cross-bars carrying buckets have been proposed; but the same is not adapted to digging wells, because the cross-arms will bind upon the vertical shaft if the weight in the buckets 125 varies. In my improvement the braces to the cross-arms and the roller-guides above and below prevent the parts from binding.

I am also aware that earth-augers have been 130 made with devices to hoist the auger upon the vertical axis.

I claim as my invention—

1. The combination of a polygonal shaft with a cage having roller-guides against the shaft,

arms extending out radially, braces to the same, a head-piece, swinging buckets connected with the arms, a collar around a neck at the upper part of the cage, and hoisting mechanism connected therewith, substantially as specified.

5. The combination, with a central vertical axis and a revolving cage formed of arms, a head-piece, and braces connecting the parts, of excavating-buckets having attaching-bolts and a weight on one side, for the purposes and as set forth.

10. The cage having a head, radial arms, and braces, in combination with the vertical axis and the guiding-rollers, the buckets, and the 15 knives, plows, or forks connected to the arms of the cage, substantially as set forth.

15. The combination, in a well-digging appa-

ratus, of the steining, the platform, the hinged flaps, the framing, the vertical axis supported at the upper end by the framing, the cage, 20 buckets, and plows, or forks upon the cage, apparatus for hoisting the cage, and hand-spikes for rotating the axis, substantially as set forth.

25. The steining for wells having the lower edge slotted, substantially as and for the purposes specified.

Signed by me this 3d day of October, A. D. 1882.

BENJ. F. STEPHENS.
